UNITED STATES PATENT OFFICE.

BENGT M. W. HANSON, OF HARTFORD, CONNECTICUT, ASSIGNOR TO THE WINKLEY COMPANY, OF HARTFORD, CONNECTICUT, A CORPORATION OF CONNECTICUT.

OIL-CUP.

SPECIFICATION forming part of Letters Patent No. 697,082, dated April 8, 1902.

Application filed June 15, 1901. Serial No. 64,667. (No model.)

To all whom it may concern:

Be it known that I, BENGT M. W. HANSON, a citizen of the United States of America, and a resident of Hartford, in the county of Hartford and State of Connecticut, have invented 5 certain new and useful Improvements in Oil-Cups, of which the following is a specification.

This invention is an improved cup for supplying oil or other lubricant to the bearings 10 or journals of machinery of various kinds, the object being to provide a simple, inexpensive, and compact oil-cup which may readily be opened by the nose of the oil-can or by the 15 finger and thumb of the operator for the introduction of oil and which when opened will receive oil from any side of the cup at which the oil may happen to be introduced, which 20 closes automatically upon the withdrawal of the can, and which when closed completely excludes dust, grit, and the other foreign substances which are liable to accumulate on and 25 around the lubricated portions of machinery.

Figure 1 is a side view of one form of my improved cup. Fig. 2 is a side view of the 25 same cup in section taken from its longitudinal center, showing the cup in its closed position. Fig. 3 is a view similar to that of Fig. 2 with the cup in its open or oil-receiving position. Fig. 4 is a modified form of this cup.

30 The cup illustrated in Figs. 1 to 3, inclusive, will first be described. The oil-receiving body portion 6 is at its lower end adapted to be screwed into a bearing by means of a wrench. This body is provided with an internally-supported head 7, forming a cover for 35 the cup, which for convenience of manufacture and assembling is preferably made in a separate piece, as herein shown, and is attached to the body by a screw-threaded stem 40 8. When employed as a reservoir-cup, as herein shown, the stem may also constitute the feeding-tube for the oil and be provided with a piece of wicking 9, which passes through the longitudinal center of the stem 45 or feeding-tube and extends out into the body or reservoir portion of the cup through the opening 10. When employed as an ordinary oil-cup, the hole 10 should be near the bottom of the cup, so as to allow the oil to flow 50 out by gravity instead of flowing by capillary

attraction, as with the use of the wick. The thimble 11 is fitted to slide like a telescope-tube upon the body of the cup, either upon the inner wall thereof or preferably, as is herein shown, upon the outside of the body. 55 The extent of the sliding movement is shown by a comparison of Figs. 2 and 3, being sufficient to permit the introduction of the nose of an oil-can when in the latter position. When closed, as shown in Fig. 2, the thimble 60 effectually confines the oil contained in the body and also excludes dust and grit from the exterior. In order to make the cup self-closing, which is preferable in most cases, it is provided with a spring 12, which rests within 65 the body of the cup and abuts against an annular shoulder 13 of the thimble, which extends inwardly over the wall of the body of the cup far enough to receive the spring. This shoulder may also abut against the top 70 of that wall and serve as a stop for the downward or open position of the thimble, as shown in Fig. 3. The exterior of the thimble is preferably knurled or checked, as shown in Figs. 1 and 4, so that it may readily be grasped by 75 the finger and thumb of the operator to open the cup when the latter is in a position accessible to the finger and thumb. The aperture in the upper end of the thimble, which encircles the stem 8, is made larger than that 80 stem and is preferably flared or countersunk, as indicated at 14, so as to provide ample opening for receiving the required volume of oil from the oil-can. The annular form of this opening enables the oil to be applied 85 from any side, so that it is not necessary for the operator to apply the oil-can at any particular side of the cup or to turn the cup or the thimble to any particular position for receiving the oil.

90 Where the cup is so located that it is difficult to reach it with the finger and thumb or where for this or any other reason it is desirable to employ but one hand for the oiling operation, the cup shown in Fig. 4 may be 95 employed. In that cup the joint between the cover 15 and the thimble 16 is beveled or flared, so that they may be forced apart by the nose 17 of an oil-can, which will then be in position for filling the cup, after which 100

upon withdrawal of the can the thimble will be closed by its spring. This figure also shows another modification of the cup in the respect that the screw and squared portion 5 are omitted, the plain stem 18 being intended to be driven into a hole drilled in the bearing.

I claim as my invention—

1. An oil-cup comprising a body portion having an annular outwardly-extending internally-supported cover, and a telescoping thimble mounted on the body below the cover to close against the cover.
2. A self-closing oil-cup, comprising a body portion having an annular outwardly-extending internally-supported cover, a telescoping thimble mounted on the body below the cover, to close against the cover, and a spring for resiliently holding the thimble to its cup-closing position.
3. In an oil-cup, the combination of an oil-receiving body, provided with an upwardly-extending stem having an annularly-extending head, forming a cover for the cup, and a telescoping thimble mounted upon the body to close against the cover.
4. A self-closing oil-cup, comprising an oil-receiving body portion, a cover comprising an annular head attached to the body by a reduced stem, a telescoping thimble mounted upon the body to close against the head, and a spring for resiliently holding the thimble in its closed position.
5. An oil-cup comprising an oil-receiving body portion, provided with an internally-

supported annularly-extending head forming 35 a cover for the cup, and a telescoping thimble mounted upon the body below the cover, having an annular shoulder forming a stop for the opening movement of the thimble.

6. A self-closing oil-cup, comprising an oil-receiving body portion, having an internally-supported annularly-extending head forming a cover for the cup, a telescoping thimble mounted upon the body, provided with a shoulder extending annularly over the wall 40 45 of the body of the cup, to form a stop for the downward movement of the thimble, and to form a shoulder for a spring, and a spring for engaging with the said shoulder to resiliently hold the thimble in its cup-closing position. 50

7. The combination, in an oil-cup, of an internally-supported annular cover therefor, and a thimble resiliently closing against the cover, with a flaring joint to be wedged open by the nose of an oil-can. 55

8. The combination, in an oil-cup, of an annular cover, secured to the body of the cup by a reduced stem, a thimble closing against the cover and encircling the stem with an annular outwardly-flaring opening, for receiving the oil. 60

Signed at Hartford, Connecticut, this 14th day of June, 1901.

BENGT M. W. HANSON.
